United States Patent Office

Des. 212,341
Patented Oct. 1, 1968

212,341

WALL PANELING

William C. Heirich, 2912 Wauhilah Drive,
Muskogee, Okla. 74401

Continuation-in-part of design application Ser. No.
4,525, Nov. 2, 1966. This application Oct. 27, 1967,
Ser. No. 9,675

Term of patent 14 years

(Cl. D54—2)

FIG. 1

FIG. 2

FIG. 3

FIG. 4

FIGURE 1 is a perspective view of a portion of an individual panel;

FIGURE 2 is a cross-sectional view of an individual panel;

FIGURE 3 is a top view of a portion of the panel taken along lines 3—3 of FIGURE 2; and

FIGURE 4 is a sectional view taken along lines 4—4 of FIGURE 2.

This is a continuation-in-part of design application Ser. No. D. 4,525, filed Nov. 2, 1966 and now abandoned.

I claim:

The ornamental design for wall paneling, as shown.
